MAUREY L. WEBSTER, OF SANTA MONICA, CALIFORNIA

WALL CONSTRUCTION

Application filed March 19, 1930. Serial No. 437,041.

My invention relates to a wall construction suitable for a furnace or other structure in which one side of the wall is heated to a high temperature.

5 A considerable difficulty has been experienced in connection with walls of furnaces made of bricks or blocks which are usually made with the fire or refractory bricks or blocks forming the inside wall and common 10 bricks forming the outside portion of the wall. It has been more or less common practice to set up the refractory block part of the wall without adequate expansion joints for the blocks, frequently with the blocks in contact, which does not allow for the expansion 15 of these refractory blocks when subjected to the high temperature of the furnace. If the bricks are imbedded in mortar and have mortar vertical joints this mortar disintegrates 20 at the high temperatures; such disintegration applies to fire clay mortar beds as well as the ordinary lime and cement mortar beds. The disintegrated joint material then falls off the joints between the refractory blocks or sifts 25 downwardly forcibly pressing the blocks inwardly. Adjacent the side subjected to the highest temperature the blocks or bricks expand to greater extent than the portion of the blocks or bricks which is imbedded in the wall: this causing the blocks or bricks to 30 have a somewhat wedge shape and in a large wall this bows inwardly having a convex interior curve, considered horizontally and vertically, forming in effect an inward bulging 35 of the wall from end to end and from top to bottom. This has been found to progress until the wall either falls in or requires to be taken down and rebuilt.

An object therefore of my invention is to construct a block or brick wall for a furnace having a refractory block lining with a common block or brick construction for the outside portion of the wall and to bed the refractory blocks in such a manner that the expansion is taken care of between the joints of the refractory blocks and such blocks, when fully expanded do not press against each other with sufficient force to cause a bulging inwardly of the wall. A feature therefore of my invention in this connection is in bedding

the blocks in layers using a fire clay mortar, this being mixed to the proper consistency with water and leaving the vertical joints between the blocks without any mortar. The common blocks or bricks are bonded into the 55 refractory blocks or bricks using a mortar joint and bedding of the ordinary type. Therefore by this construction when the wall is subjected to heat the water of crystallization is driven out of the fire clay mortar and causes this to contract usually about 50% and in fact to disintegrate to a certain extent adjacent the inside of the wall which is subjected to the greatest temperature.

This leaves the joints between the refractory bricks or blocks on the inside practically open and gives room for expansion of the blocks or bricks considered both horizontally and vertically. The size of the joints is calculated so that in any expansion which may occur there will not be sufficient pressure from one block to the other to cause the inward bulging of the wall.

Another feature of my invention comprises a construction by which the wall is bound to an exterior metal construction. Such binding is preferably by means of an anchor bar which engages the exterior metal construction and is bound into the brick or block work, engaging the inside of the common bricks or blocks. In this construction I preferably use angle bars which have one flange imbedded in a horizontal joint or bed between adjacent beds or layers of bricks or blocks and with the other flange extending downwardly of 85 the outside face of the wall. The angle straps are preferably in the form of a Z shape and engage the outside of the angle bars and the interior of the wall.

My invention is illustrated in connection with the accompanying drawing in which,

Fig. 1 is a partial elevation showing the inside of the wall,

Fig. 2 is a partial elevation showing the outside of the wall,

Fig. 3 is a vertical section on the line 3—3 of Fig. 1 in the direction of the arrows,

Fig. 4 is a partial horizontal section on the line 4—4 of Fig. 3 in the direction of the arrows,

Fig. 5 is a partial horizontal section on the line 5—5 of Fig. 3 in the direction of the arrows,

Fig. 6 is a perspective view of one of the 5 anchor straps,

Figs. 7 and 8 illustrate the type of hatching and surfacing used to indicate the refractory and the common blocks or bricks.

In the drawing the refractory blocks or 10 bricks are designated by the numeral 11, these being on the inside of the wall and the common blocks or bricks 12 forming the outside portion of the wall. In the illustration the refractory blocks are imbedded 15 in mortar 13 preferably made of fire clay mixed with water to the proper consistency to hold one layer of bricks on another with the proper spacing of the bed. When bricks are used the common bricks are usually 20 slightly thinner than the refractory bricks so that the joint 14, between the common bricks, is thicker than for the refractory bricks. This joint is usually made of lime mortar 25 and to hasten the setting a certain amount of cement is added.

In the illustration, the inside wall is layed 30 up with rows of headers 15 and alternate rows of stretchers 16. The outside wall is illustrated also as being layed with rows of headers 17 and rows of stretchers 18. The particular wall illustrated is two-and-one-half bricks thick, considering the length of the bricks in the measurement, but a satisfactory wall for certain purposes can be readily made two bricks thick and the thickness can be increased where necessary.

In laying up the refractory bricks or 40 blocks these are butted together in the interior of the wall, as indicated at 19, and the common blocks or bricks will also butt 45 against the refractory blocks or bricks, as indicated at 20. The common blocks have vertical mortar interior joints 21 and have vertical joints 22 being imbedded or filled 50 with mortar. However the vertical joints 23 of the refractory blocks or bricks are open spaces without any fire clay or other mortar. In laying up a wall of this character it is preferable to use guide-spacers to space the 55 blocks the proper distance apart until the bricklayer becomes skilled in this type of wall construction. It will be noted that this type of bonding gives a diagonal supporting bond considering from the exterior to the 60 interior of the wall. Therefore after the fire clay beds 13 have contracted, and to a certain extent disintegrated, the blocks facing the interior of the furnace are still properly supported.

60 In addition to this construction I use metal bars to prevent inward bulging of the wall, such bars are designated generally by the numeral 24 and consist of angles having a flange 25 extending into the mortar bed between 65 layers of brick and having an outside flange

26 extending downwardly over the face of the layer of bricks or blocks. These bars are quite long and usually reach from one corner to the other corner of the furnace and therefore may be considered as supported at the corners. 70 However, the brick wall will be free to bulge inwardly as the flange 25 will slip in its mortar bed. In order to anchor the wall to these bars I utilize anchor straps 27: These are illustrated as having a web 28 with flanges 29 forming a Z shaped bar. One of the flanges is caught over the outside flange of the angle bar, the web fits in the mortar space between adjacent layers of common brick or block and the other flange fits behind the inner end of 80 one of the common blocks or bricks and in a wall of the thickness illustrated preferably behind one of the header blocks or bricks, such header being cut a little short to give space to accommodate the thickness of the flange 29. 85 The joint space above the flange, indicated at 30, may be filled with mortar.

With a wall of this construction the interior is usually subjected to a very high temperature which causes a complete drying of 90 the fire clay bed for the bricks adjacent the inner wall, driving off the water of crystallization which allows a contraction of this fire clay of frequently more than 50%. The fire clay also in a sense disintegrates having no 95 bonding action, and a certain amount, due to the gas and air blasts in the furnace, will fall out of the inside joints. Therefore a certain amount of the fire clay in the joints 13 adjacent the inside wall is reduced in thickness 100 and strength or altogether disappears so that for practical purposes the horizontal layers of the refractory bricks or blocks on the inside have an open joint. The vertical joints 23 have been left open so that when the interior bricks or blocks expand such expansion can take place until these open joints are closed without the adjacent blocks or bricks 105 contacting and should they come in contact the expansion has usually been sufficiently 110 taken care of so that there is insufficient force to bulge the wall inwardly. On contraction of the blocks or bricks they return to their original condition. Manifestly some of the 115 heat is conducted to the interior of the wall but the refractory blocks or bricks have sufficient room for expansion without damage to the wall.

Should there be a tendency for the wall to 120 bulge inwardly, due to the expansion forces, the anchor straps 27 exert a pull on the angle bars 24, which, as above mentioned, are supported at opposite ends and are of the proper strength to resist the inward bulge of the 125 wall. The bonding of the bricks is sufficient so that considerable stress may be transferred to the anchor straps. The bars 24 are free to expand longitudinally and in transverse directions without injuring the wall whatever. The anchor straps 27 can also expand 130

without any injury to the wall but the metal parts are not subjected to high temperatures and in fact function somewhat as heat radiating portions in the wall. In building the wall the bars 24 are placed distances apart found to be suitable by practice. The anchor straps are also positioned as has been found necessary.

In building walls of the above type it is desirable to have the common blocks of lesser thickness than the refractory blocks and when the common blocks are of less thickness than the refractory blocks the bedding joints must be made sufficient thickness for the common blocks so that they bed in aligning layers with the refractory blocks. If for any reason the refractory and the common blocks or bricks are of materially different thicknesses the common blocks should be bedded so that at any layer of the refractory blocks there will be a bedding joint for both the refractory and common blocks. It is obvious that if desired I may build the wall so that the horizontal bedding joint for the refractory blocks or bricks on the inside is left without a supporting mortar and the vertical joints may also be left without a supporting mortar, or if desired these vertical joints may have mortar placed therein such as fire clay which under heat will dry out and contract and to a certain extent disintegrate. Any type of joint for the refractory blocks or bricks is suitable which will allow for the free expansion of the heated end and the remaining portion of these blocks or bricks so that undue pressure is not exerted between adjacent blocks or bricks and thus the inward bulging of the wall is prevented.

I claim as my invention:

1. A furnace wall having refractory blocks on the inside, the common blocks on the outside and common blocks being bedded in a mortar bed and bonding with the refractory blocks, mortar bedding for the refractory blocks having a characteristic of allowing considerable shrinkage when subjected to the temperatures of the furnace and shrinking away from the joint thereby leaving open joints between the refractory blocks on the inside of the furnace wall, which joints accommodate the expansion of the refractory blocks due to the heat of the furnace.

2. A furnace wall formed of refractory blocks on the inside and common blocks on the outside, the common blocks being bedded in mortar, the refractory blocks having mortared beds formed of fire clay, the refractory and common blocks bonding together such fire clay having the characteristic of considerable shrinkage adjacent the inside surface of the wall when subjected to the furnace temperatures, thereby leaving joints with sufficient space for the expansion of the refractory blocks adjacent the inside surface of the furnace without said blocks exerting excessive pressure one against the other.

3. A furnace wall having refractory blocks on the inside and common blocks on the outside, the common blocks being bedded in mortar, the refractory blocks having bedding of material adapted to shrink when subjected to high temperatures, said bedding forming joints between some of the refractory bricks on the inside surface of the wall other joints on the inside surface being open, the refractory and common blocks being bonded together the said joints affording a space for the expansion of the refractory blocks when subjected to the furnace temperatures without said blocks exerting sufficient pressure one against the other to cause an inward bulging of the wall.

4. A furnace wall having refractory blocks or bricks on the inside and common blocks or bricks on the outside, the outside blocks being bedded on mortar beds and having mortar vertical joints, the refractory blocks being bedded on horizontal beds formed of fire clay, the refractory and common blocks bonding together there being vertical open joints between the refractory blocks on the inside of the wall, the fire clay having the characteristic of considerable shrinkage when subjected to high furnace temperatures whereby the horizontal and vertical joints afford a space for the expansion of the inner portion of the refractory blocks without such blocks exerting sufficient pressure one against the other to develop a wedge shape and bulge the wall inwardly.

5. A furnace wall having refractory blocks on the inside and common blocks on the outside, the refractory blocks being bedded in layers and the common blocks being bedded with mortar in layers whereby the refractory and common blocks have a horizontal bedding in the same plane the said refractory and common blocks being bonded together the refractory blocks being built into the wall with joints on the inside surface such joints forming a space for the expansion of the refractory blocks when subjected to the heat of the furnace thereby preventing sufficient pressure of the refractory blocks one on the other to cause inward bulging of the wall.

6. A furnace wall having refractory blocks on the inside and common blocks on the outside, common blocks being bedded in horizontal layers with a mortar bedding, the refractory blocks having layers with a horizontal bedding formed of fire clay or the like, said horizontal bedding being in the same horizontal plane for the refractory and the common blocks, the refractory blocks having open vertical joints on the inside the fire clay adjacent the inside of the furnace being adapted to contract when subjected to furnace temperatures, and horizontal joints with sufficient space whereby, with the vertical joints, provision is made for expansion of the refractory blocks.

7. A furnace wall having refractory blocks on the inside and common blocks on the outside, common blocks being bedded in horizontal layers with a mortar bedding, the refractory blocks having layers with a horizontal bedding formed of fire clay or the like, said horizontal bedding being in the same horizontal plane for the refractory and the common blocks, the refractory blocks having open vertical joints on the inside, the fire clay adjacent the inside of the furnace being adapted to contract when subjected to furnace temperatures, and horizontal joints with sufficient space whereby, with the vertical joints, provision is made for expansion of the refractory blocks there being metal supporting structures on the outside of the furnace and anchors extending from said metal structures and bonding in the interior of the wall.

8. A furnace wall formed of blocks built up on mortar beds, angle bars on the outside of the wall each having a flange fitting in a mortar bed with a flange on the outside of the wall and metal anchors engaging the outside flange and having a bond in the interior of the wall, the anchors being formed of Z shaped straps having a flange engaging the flange of the bars and an interior flange fitting in a joint between adjacent blocks in the interior of the wall.

9. A furnace wall having refractory blocks on the inside and common blocks on the outside, the common blocks being bedded in mortar, said blocks being bonded together, an angle bar extending along the outside surface and having a flange fitted in one of the beds between the common blocks and having another flange on the outside surface, and metal anchors formed of Z shaped straps with an outside flange engaging the flange on the outside of the angle bar and having an interior flange extending in a joint between blocks in the interior of the wall.

10. A furnace wall having refractory blocks on the inside and common blocks on the outside, the common blocks being bedded in mortar, said blocks being bonded together, an angle bar extending along the outside surface and having a flange fitted in one of the beds between the common blocks and having another flange on the outside surface, and metal anchors formed of Z shaped straps with an outside flange engaging the flange on the outside of the angle bar and having an interior flange extending in a joint between blocks in the interior of the wall, the refractory blocks having a bedding of material adapted to shrink when subjected to high temperatures and leave substantially open joints between the refractory blocks on the inside of the wall whereby the refractory blocks may expand, said joints accommodating the expansion of the refractory blocks.

11. A furnace wall having refractory blocks on the inside and common blocks on

the outside, the common blocks having a bedding of mortar, the refractory blocks having bedding of fire clay, said blocks bonded together there being open vertical joints between the refractory blocks on the inside of the wall, metal angle bars on the outside of the wall each having a flange fitted between adjacent common blocks with an outside flange on the outside face of the common blocks, and anchor straps having an outer flange engaging the outer flange of the bar with a web between the common blocks and with an inner flange binding in a vertical joint of the common blocks of the wall, the joints in the refractory blocks accommodating the expansion of such blocks.

12. A furnace wall having refractory blocks on the inside and common blocks on the outside, the common blocks being bedded in mortar beds, means to support the refractory blocks with the contiguous blocks spaced apart, forming open joints on the inside of the wall, said open joints affording a space for the expansion of the inside portion of the refractory blocks due to the temperature of the inside of the furnace.

13. A furnace wall having refractory blocks on the inside and common blocks on the outside, the common blocks being bedded in a mortar bed and bonding with the refractory blocks, a bedding for the refractory blocks supporting and spacing the surfaces of contiguous blocks apart, the bedding for the refractory blocks having the characteristic of allowing for considerable shrinkage when subjected to the temperatures of the furnace and thereby forming open joints on the inside of the furnace between the refractory blocks to accommodate the expansion of such blocks due to the heat of the furnace.

14. A furnace wall having refractory blocks on the inside and common blocks on the outside, the common blocks being bedded on a mortar bed and bonding with the refractory blocks, the bedding for the refractory blocks spacing adjacent blocks apart in horizontal rows, there being open vertical joints between the refractory blocks, the bedding having the characteristic of allowing considerable shrinkage when subjected to the temperatures of the furnace and thereby leaving the portion of the horizontal joints adjacent the inside surface of the furnace open, which horizontal open joints and the vertical open joints provide room for expansion of the refractory blocks on the inside of the furnace due to the heat of such furnace.

15. A furnace wall formed of refractory blocks on the inside and common blocks on the outside, the common blocks having a mortar bedding, there being vertical internal joints between the common and the refractory blocks on the inside of the furnace, a metal bar extending along the outside wall, a metal anchor having one end engaging such

bar having a central portion embedded in a joint of the common blocks and having an inner end fitting in the internal joint between the common and the refractory blocks.

- 8 16. A furnace wall formed of refractory blocks on the inside and common blocks on the outside, said common blocks having horizontal joints with a mortar bedding, a bar extending along the outside of the furnace, a 70
10 metal anchor having an outside portion engaging said bar, a central portion bedded in the horizontal joint of the common blocks, the said common blocks and refractory blocks meeting with a vertical joint and the inner 75
15 end of the anchor having an end extending into one of said joints.

17. A furnace wall formed of refractory blocks on the inside and common blocks on the outside, the common blocks being bedded 80
20 in mortar and having horizontal joints, there being vertical internal joints at the abutting ends of the refractory and common blocks, an angle bar on the outside of the furnace having one flange extending in the horizontal mortar joint of the common blocks and the other 85
25 end extending on the outside face of the wall, a Z shaped metal anchor having a central portion in the horizontal metal of the common blocks and one end bent over the angle
30 and the other end extending into the joint between the abutting ends of the common and refractory block.

18. A furnace wall as claimed in claim 17, the refractory blocks having horizontal 90
35 layers with a bedding, said bedding supporting the adjacent blocks spaced apart, the said bedding having the characteristic of shrinking when subjected to the heat of the furnace and forming open horizontal and
40 vertical joints of the refractory blocks on the inside of the wall, the open joints providing for expansion of the refractory blocks due to the heat of the furnace.

19. A furnace wall formed of blocks with 100
45 refractory blocks on the inside, said blocks having a horizontal mortar bedding between the layers of blocks and vertical joints, a metal bar extending along the outside of the wall, a metal anchor having one end engaging 105
50 such bar and having an inner end portion embedded in a vertical joint, the mortar bedding for the refractory blocks on the inside of the wall having the characteristic of allowing considerable shrinkage when subject to the temperature of the furnace and 110
55 shrinking away from the joint, thereby leaving open joints between the refractory blocks on the inside of the furnace wall, which joints accommodate the expansion of the refractory
60 blocks due to the heat of the furnace.

20. A furnace wall formed of blocks, the blocks on the inside of the wall being refractory and having a horizontal mortar bedding between the layers of blocks and vertical 115
65 joints between adjacent blocks, a metal angle

on the outside of the furnace extending along such outside wall, means to anchor said bar in the bedding of the blocks, the bedding between adjacent layers of refractory blocks spacing such blocks apart, and the 70
75 mortar bedding having the characteristic of shrinking when subjected to the heat of the furnace and forming open horizontal joints of the refractory blocks on the inside of the wall, the open joints providing for expansion of the refractory blocks due to the heat of the furnace.

21. A wall formed of blocks, the inside blocks being refractory, a horizontal mortar bedding for the layers of blocks and a mortar 80
85 for the vertical joints between the blocks, a metal bar extending along the outside of the wall and having a flange extending into the horizontal bedding, and means to anchor the bar and such latter flange in the wall, the 90
95 mortar bedding supporting the adjacent blocks spaced apart, said bedding having the characteristic of shrinking when subjected to the heat of the furnace and forming open horizontal and vertical joints of the refractory blocks on the inside of the wall, the open joints providing for expansion of the refractory blocks due to the heat of the furnace.

22. A furnace wall formed of blocks, the blocks on the inside being refractory, a horizontal mortar bedding for the different layers of blocks, the vertical joints of the blocks also having a mortar bedding, a metal angle 100
105 extending along the outside of the wall having one flange extending in the horizontal bedding adjacent the outside wall, a Z-shaped bar engaging said angle and having one end fitting between adjacent blocks of a layer, said bedding supporting the adjacent blocks spaced apart, the said bedding having the characteristic of shrinking when subjected to the heat of the furnace and forming open horizontal and vertical joints of the refractory blocks on the inside of the wall, the open 110
115 joints providing for expansion of the refractory blocks due to the heat of the furnace.

In testimony whereof I have signed my name to this specification.
